UNITED STATES PATENT OFFICE.

WILLIAM S. SULLIVAN, OF PHILADELPHIA, PENNSYLVANIA.

ROTARY GAS ENGINE.

Application filed November 14, 1924. Serial No. 749,901.

The invention relates to rotary gas engines, and has as an object the provision of a gas engine or an internal combustion engine of this type which shall have a minimum of moving parts.

A further object of the invention is the provision of a motor of this type which shall operate without valves.

A further object of the invention is the provision of a novel cooling means for an engine of the type involved.

A further object of the invention is the provision of a motor which shall have an extremely simple and efficient provision for igniting the explosive charge.

A further object of the invention is the provision of a motor which readily lends itself to duplication upon a single shaft.

A further object of the invention is the provision of a motor with which it is possible to apply the Diesel principle of automatic ignition.

Still further objects of the invention are the provision of a motor which shall be cheap to produce and little likely to get out of order.

Further objects of the invention will appear from the following description when read in connection with the accompanying drawing, in which

Fig. 1 is a side elevation showing the shaft in section.

Fig. 2 is a central vertical section on line 2, 2 of Fig. 1.

Fig. 3 is a face view of the stator.

Fig. 4 is a side elevation of the rotor from the side opposite the showing of Fig. 1.

Figs. 5 and 6 are detail sections through the ignition apparatus, Fig. 6 showing a modification for application of the Diesel principle.

Fig. 7 is a face view of the rotor removed from the stator, the shaft shown in section.

Fig. 8 is a vertical section on line 8, 8 of Fig. 2 showing the rotor removed from the stator.

Fig. 9 is a side elevation on a reduced scale showing two of the devices placed in tandem upon a single shaft, and

Fig. 10 is a detail section on line 10—10 of Fig. 8 showing the opening from an expansion chamber upon an enlarged scale.

As shown, the device comprises a stator 10 and a rotor 11. The stator comprises a

base 12 and a vertical plate-like member 13, 55 desirably provided with bracing abutments 14 cast integral with the plate and with the base.

To make a tight joint with the rotor the stator is desirably formed with an annular flange 15 within which the rotor fits, and to further assist in preventing leakage the stator is shown as formed with a series of ring grooves 16, wherein rings 16', in the nature of piston rings are placed.

To further assist in preventing leakage the face of the plate 13 is formed with grooves which are in the nature of enlargements of portions of the piston ring grooves, into which grooves annular projections 65 upon the rotor seat. These grooves are shown at 17.

The rotor comprises an annular member having a plurality of air channels 18, 18', 19, 19', 20, 20', formed in its body and closed at their edges by walls 58, 59, with one or more explosion chambers, two being shown, as 21 and 22. A single explosion chamber could be used, or a number larger than two, the desirable number being determined to some extent by the dimensions of the motor.

The wall 23 having the openings 53 therein will be understood as forming a series of wide spokes for the support of the annular member of the rotor upon the shaft 24 and the size of the openings 53 may be whatever desired to provide the requisite amount of escape of air from the cooling chambers 75 20, 20'.

The action of the motor depends upon the escape of gases under pressure from the explosion chambers 21 and 22, through the outlets or nozzles 25, 26. These nozzles are shown as slits occupying a position parallel 85 with the axis of the shaft 24, and discharge into a channel 27 to exhaust ports 28, 29, which are provided in number to equal the number of the explosion chambers. If the explosion be allowed to take place with the 90 nozzles full open the impulse would be uneven in character, being a series of pushes rather than a steady push, as is desirable.

To graduate the escape of the gases, cut-off plates 30, 31, are shown carried by and projecting from the stator and standing in the channel 27. When the nozzles 25, 26 stand opposite the full portion of the cut-

off plates 30, 31, the nozzles will be closed, and during the revolution of the rotor in the direction indicated by the arrows the nozzles will pass away from the cut-off plates and thereby be opened.

To provide for a gradual opening of the nozzles, the cut-off plates are shown as tapered at 32, 33, either upon a straight line or upon any desirable curve, according to the 10 character of the impulse desired. Thus the escape of gases at their greatest pressure will have a minimum of the nozzle from which to escape, and as the pressure lowers the size of opening of the nozzle will increase, whereby to keep the reactive impulse of the gases substantially uniform 15 throughout.

Except for the desirability of equaling the 20 impulse and the desirability of holding the pressure within the explosion chamber until the combustion is completed, the cut-off plates 30, 31 might be omitted, and the entire channel 27 might be treated as an exhaust port.

25 To admit an explosive charge to the explosion chambers intake ports 34, 35 are shown. To these intake ports when the motor is in service, an explosive mixture of fuel and air under considerable pressure 30 will be supplied by means of conduits 36, 37. The compression of the fuel will be carried out in a separate device (not shown) either driven by the motor which is served or otherwise as most desirable.

35 The relation of the intake ports 34, 35 to the nozzle cut-off is such, taking into consideration the circumferential extent of the explosion chamber from its closed end to the nozzle, that the fresh mixture of fuel 40 will be admitted to the explosion chamber an instant before the closure of the nozzle by the cut-off plate. This provides for scavenging of the chamber and for a slight amount of cooling thereof. As the chamber 45 passes the intake port a charge of compressed gaseous fuel is introduced into it, and in the continued revolution of the rotor, the side of the chamber which is closed only by the face of the stator, comes opposite 50 a spark plug 38 or 39, which will be caused to produce a spark at the desired time by a timer of conventional form, not shown, which may be operated from the shaft 24,

At the time of the explosion, the chambers 21, 22, being completely closed, the combustion will be allowed to become complete before escape of the pressure is allowed to take place, as already described. If desired, exhaust conduits 40, 41 may be provided for the exhaust ports.

To cool the motor there are shown air intake ports 42, 43, for the air channel 18, 18', inlet ports 44, 45, for air channels 19, 19', and inlet ports 46, 47, for air channels 20, 20'. To direct air into these ports during

the revolution of the rotor, cups 48 are shown projecting from the rotor and standing over the inlet ports whereby during the rapid rotation of the rotor a blast of air 70 will be caused to enter the inlet ports.

At the opposite end of each of the channels mentioned there is shown an outlet port for heated air from the channels mentioned, such outlets being shown at 49, 50, 51, 52. The outlets of the channels 20, 20' are 75 through outlet 70 interior of the rotor, from which the air may escape through openings 53 in the form shown, or between spokes if a spoked form of rotor be adopted.

The air pressure generated by the cups 48 80 may be assisted if desired by a rarefaction at the outlet ports 49—52 by cups arranged with their open sides rearwardly directed, so as to produce a rarefaction in their interiors.

To improve the efficiency of the cooling action fins 54 are shown upon the exterior 85 of the walls of the explosion chamber with in the cooling air channels, and the inlets to the channels are arranged so that the entering blast of air will impinge upon these fins. Additional fins are shown at 55 upon the circumference of the rotor, and at 56, 57 on the cylindrical surfaces of the walls 90 separating the air channels from the exhaust 95 passage.

To provide for lubrication of the frictional surfaces, oil ducts 60 are shown in the plate of the stator and coacting ducts 61 extending perpendicularly thereto to the face of the stator whereby to transmit lubricant to the frictional surfaces between the stator and the rotor. In addition there is indicated a duct 62 passing into each nozzle cut-offs 100 30 and 31 and ducts 63, placing the ducts 62 in communication with the surfaces of the cut-off plates.

To utilize the Diesel principle the arrangement of Fig. 6 may be utilized, wherein a fuel jet 64 is shown to which fuel may be supplied as by means of a pipe 65. When the jet 64 is to be used it will occupy the position of the spark plug 38. With this arrangement air under pressure sufficient to cause ignition of a charge will be introduced 110 by means of the conduits 36, 37. After the air has been thus admitted and the rotor has moved from the intake ports 34, 35 sufficiently to close the explosion chamber, the chamber will come opposite the fuel jet 64 and a supply of liquid fuel under high pressure will be injected into the chamber in the manner usual with Diesel engines. Combustion will immediately take place, due to the heat generated by the pressure. The 115 rotor face seals the injector except when same is opposite the explosion chamber.

To hold the rotor in its relation to the stator a nut 66 is shown threaded to shaft 24, and a thrust bearing 67 is provided, act-

ing between the nut and the shoulder 68 upon the stator. A lock nut 69 is provided to hold the parts in adjusted position.

By the arrangement in Fig. 9 any number 5 of motors may be applied to a single shaft 24, the successive stators acting as journals for the shaft.

The operation of the device will be apparent from the above description. Minor 10 changes may be made in the physical embodiment of the invention without departing from its spirit.

I claim:

1. A rotary gas engine comprising, in combination, a stator having a face substantially perpendicular to its axis, a rotor mounted to revolve closely adjacent said face of said stator and provided with a combustion chamber having a reactance nozzle outlet, means carried by the stator to conduct fuel to said chamber.

2. A rotary gas engine comprising, in combination, a stator having a face substantially perpendicular to its axis, a shaft journaled in said stator upon the axis thereof, a rotor carried by said shaft to revolve closely adjacent said face of said stator and provided with a combustion chamber having a reactance nozzle outlet, and means to conduct fuel to said combustion chamber.

3. A rotary gas engine comprising, in combination, a stator having a face substantially perpendicular to its axis, a shaft journaled in said stator upon the axis thereof, a rotor carried by said shaft to revolve closely adjacent said face of said stator and provided with a combustion chamber having a reactance nozzle outlet, and means carried by the stator, to conduct fuel to the combustion chamber.

4. A rotary gas engine power plant comprising, in combination, a plurality of stators each having a face substantially perpendicular to its axis, a shaft journaled in said stators upon their axes, a plurality of rotors mounted on said shaft, one to revolve closely adjacent said face of each stator, each rotor provided with a combustion chamber having a reactance nozzle outlet, means to conduct fuel to each chamber.

5. A rotary gas engine comprising, in combination, a stator having a face substantially perpendicular to its axis, an open fuel supply port and an open exhaust port in said face, a rotor mounted to revolve closely adjacent said face of said stator and having a wall normally closing said ports, a combustion chamber opening through said wall and an annular exhaust chamber provided 55 with a port opening through said wall, said openings adapted to revolve past said respective ports, and means to conduct fuel to said fuel port.

6. A rotary gas engine comprising, in combination, a stator having a face substantially

perpendicular to its axis, a rotor mounted to revolve closely adjacent said face of said stator and provided with a combustion chamber, having a reactance nozzle outlet, means to provide a gradual opening of said nozzle upon rotation of the rotor, and means to conduct fuel to said combustion chamber.

7. A rotary gas engine comprising, in combination, a stator having a face substantially perpendicular to its axis, a rotor mounted to revolve closely adjacent said face of said stator and provided with a combustion chamber having a reactance nozzle outlet, means carried by the stator to provide a gradual opening of said nozzle upon rotation of the 75 rotor, and means to conduct fuel to said combustion chamber.

8. A rotary gas engine comprising, in combination, a stator having a face substantially perpendicular to its axis, a rotor mounted to revolve closely adjacent said face of said stator, and having a combustion chamber provided with a reactance nozzle outlet and an annular channel into which said nozzle opens, and stationary means standing in said channel to close the nozzle during the combustion period.

9. A rotary gas engine comprising, in combination, a stator having a face substantially perpendicular to its axis, a rotor mounted to revolve closely adjacent a face of said stator, having a combustion chamber provided with a reactance nozzle outlet and an annular channel into which said nozzle opens, and stationary means carried by the stator standing in said channel to close the nozzle during the combustion period.

10. A rotary gas engine comprising, in combination, a stator, a rotor mounted to revolve closely adjacent a side of said stator, having a combustion chamber provided with a reactance nozzle outlet and an annular chamber into which said nozzle opens, a rib carried by said stator standing in said channel and adapted to close said nozzle during a portion of the revolution of the rotor, one end of said rib beveled to provide a gradual opening of said nozzle, and means carried by the stator to conduct fuel to said combustion chamber.

11. A rotary gas engine comprising, in combination, a stator, a rotor mounted to revolve closely adjacent a side of said stator, having a combustion chamber provided with a reactance nozzle outlet and an annular chamber into which said nozzle opens, a rib carried by said stator standing in said channel and adapted to close said nozzle during a portion of the revolution of the rotor, one end of said rib beveled to provide a gradual opening of said nozzle, said annular chamber having an exhaust port, and means carried by the stator to conduct fuel to said combustion chamber.

12. A rotary gas engine comprising, in

combination, an annular rotor having a combustion chamber provided with a reactance nozzle outlet, said combustion chamber having an intake opening at a face substantially perpendicular to the axis of the rotor, means standing closely adjacent said face of the rotor to close said opening, a fuel supply nozzle opening through said last named means to deliver fuel into the combustion chamber as it passes during the revolution of the rotor, and means to ignite the charge.

13. A rotary gas engine comprising, in combination, an annular rotor having a combustion chamber provided with a reactance nozzle outlet and an opening in a face substantially perpendicular to the axis thereof, stationary means adapted to close said nozzle during a portion of the revolution, means standing closely adjacent one side of said rotor adapted to close said opening and having means opening therethrough to deliver fuel into said combustion chamber during revolution of the rotor, the time of introduction of the fuel being slightly in advance of the closing of said outlet to provide for scavenging, and means to ignite the charge of fuel in the combustion chamber.

14. A rotary gas engine comprising, in combination, an annular rotor having a combustion chamber provided with a reactance nozzle outlet, said chamber having an open side in a face of the rotor substantially perpendicular to its axis, means standing closely adjacent said face to normally close the opening, a fuel supply port in said means in circumferential alinement with said opening, and ignition means spaced from said port projecting through said closing means in circumferential alinement with said opening whereby upon revolution of the rotor fuel may be fed to the combustion chamber through said port and later be ignited by said ignition means.

15. A rotary gas engine comprising, in combination, a rotor having a combustion chamber provided with a reactance nozzle outlet, an annular expansion chamber into which said outlet opens, a substantially annular air chamber interrupted by the walls of said combustion chamber, and an air port for admitting cooling air to said channels, whereby to cool the walls of the combustion chamber.

16. A rotary gas engine comprising, in combination, a rotor having a combustion chamber provided with a reactance nozzle outlet, a substantially annular air channel interrupted by the walls of said chamber, and an air port admitting cooling air to said channel closely adjacent a wall of said chamber, whereby to effect the cooling of the wall.

17. A rotary gas engine comprising, in combination, a rotor provided with a combustion chamber having a reactance nozzle

outlet, an annular expansion chamber into which said outlet opens and a substantially annular air channel interrupted by a wall of the combustion chamber, said air channel having an inlet opening adjacent said wall, means carried by the exterior of the rotor for directing air into said opening during rotation of the rotor, whereby to cool the walls of said chambers.

18. A rotary gas engine comprising, in combination, a stator having a face substantially perpendicular to its axis, a rotor mounted to revolve closely adjacent said face thereof, and having a combustion chamber provided with a reactance nozzle outlet, said chamber having an opening normally closed by the wall of the stator, means to preserve a tight joint at each side of the travel of said opening, a fuel supply port in said stator, in circumferential alinement with said opening, and ignition means carried by the stator spaced from said port and also in circumferential alinement with said opening.

19. A rotary gas engine comprising, in combination, a rotor provided with a combustion chamber having a reactance nozzle outlet, an annular expansion chamber into which said outlet opens and a substantially annular air channel interrupted by a wall of the combustion chamber, said air channel having an inlet opening adjacent said wall and an outlet opening, means carried by the exterior of the rotor for directing air into said inlet opening during rotation of the rotor, and means carried by the rotor to produce rarefaction of air at the outlet of said air channel, whereby to cool the walls of said chambers.

20. A rotary gas engine comprising, in combination, a rotor having a combustion chamber provided with a reactance nozzle outlet, said rotor also having an annular expansion chamber and a substantially annular cooling medium channel, said chamber and channel having a common wall, means to supply cooling medium to said channel to cool the said wall of said chamber, and means to supply fuel to said combustion chamber.

21. A rotary gas engine comprising, in combination, an annular rotor having a combustion chamber provided with a reactance nozzle outlet opening substantially tangential to a wall of the annular rotor, said rotor also having a substantially annular channel for cooling medium, and means to supply a cooling medium to said channel into contact with the walls of the combustion chamber and nozzle.

22. A rotary gas engine comprising, in combination, a stator having a face substantially perpendicular to its axis, a rotor mounted to revolve closely adjacent said face of said stator and having a combustion

chamber provided with a reactance nozzle rotor, and means to supply lubricant to the outlet, means to supply fuel to said combustion chamber, and means to supply lubricant to the opposed surfaces of stator and 5 rotor.

23. A rotary gas engine comprising, in combination, a stator having a face substantially perpendicular to its axis, a rotor mounted to revolve closely adjacent said 10 face of said stator, having a combustion chamber provided with a reactance nozzle outlet and an annular expansion chamber, a rib carried by the stator standing in said expansion chamber to close said nozzle 15 during a portion of the revolution of the

rotor, and means to supply lubricant to the surface of said rib.

24. A rotary gas engine comprising, in combination, an annular rotor having a plurality of expansion chambers, each having 20 an inlet opening at a side substantially perpendicular to the axis of the rotor and a reactance nozzle outlet, means standing closely adjacent to said side of the rotor to close said openings, and fuel conducting 25 means, carried by said first-named means to conduct fuel under pressure to said openings during their passage upon revolution of the rotor.

WILLIAM S. SULLIVAN.
